Primary Examiner — Ryan Harvey(74) *Attorney, Agent, or Firm* — Dunlap Bennett & Ludwig PLLC(57) **CLAIM**

The ornamental design for a casino table game, as shown and described.

DESCRIPTION

The sole FIGURE is a top plan view of a casino table game, showing my new design.

The broken lines shown in the drawings depict portions of the casino table game that form no part of the claimed design.

It is to be understood that the surface of the tabletop of the casino table game, between the outer broken line and the claimed lines, forms no part of the claimed design.
